PAGE 2

Fig. 2

Fig. 3

FIGURE 1 is a perspective view of an artificial tree showing our design. The tree presents the same appearance from all angles.

FIGURE 2 is a view of one of the removable branches of the tree, and

FIGURE 3 is an enlarged view of the upper portion of FIGURE 2.

The characteristic feature of our design resides in the specific removable branches spaced about a trunk, each branch comprising a series of transversely crimped foil needles or fingers extending outwardly along its length and terminating in a foil sun-burst effect at its tip, all as shown.

We claim:

The ornamental design for an artificial tree, as shown and described.
